UNITED STATES PATENT OFFICE.

STEPHEN S. NEWTON, OF BINGHAMTON, NEW YORK.

BOTTLE-STOPPER.

SPECIFICATION forming part of Letters Patent No. 245,858, dated August 16, 1881.

Application filed June 23, 1881. (Model.)

To all whom it may concern:

Be it known that I, STEPHEN S. NEWTON, a citizen of the United States, residing at Binghamton, in the county of Broome and State of New York, have invented certain new and useful Improvements in Bottle-Stoppers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 is a vertical section of my improved bottle-stopper. Fig. 2 is a vertical section of a modification thereof.

In the drawings, A A² is the discharging-tube, the lower portion, A, being screw-threaded to receive the cork-tube D, and provided with a flange, A', to cover the mouth of the bottle. The upper part, A², of the discharge-tube is externally screw-threaded at its upper end, the extreme upper end being closed by a flat plate, a, in which are formed ports a' at some distance each side of its center.

B B' is a hood, consisting of a tube-section, B', and a flat surface, B, adapted to fit over and close the ports a'.

b is a central discharge-port formed in the hood. The exterior surface of the portion A², which is below the screw-threads, is smooth, to present a more finished appearance when the hood is screwed up to discharge the liquid than it would present if the screw-threads extended down to the flange A'. This construction also permits the lower edge of the tube-section B' of the hood to be turned inwardly against the part A², as at b², and engaged with the shoulder formed by the threads, and thus prevent the removal of the hood.

C is a washer fitting closely within the hood, and having a port, c, corresponding to the discharge-port b, and serving to close the ports a' closely when the hood is screwed down.

In Fig. 2 I employ an internally-screw-threaded flange, A³, depending from the flange A', to fit upon the neck of the bottle, and discharge the liquid through a port, b', formed centrally in the upper part of the hood by dispensing with the tip through which the port b is formed in Fig. 1, the construction shown in Fig. 2 possessing some advantages over that

shown in Fig. 1 when used for discharging finely-powdered or other substances which will not flow freely through the tip shown in Fig. 1. 55

a² is a spur projecting upwardly from the center of the cap of the tube A², in which the ports a' are formed, and, entering the ports b', effectually prevents the entrance of dirt at this point when the cap is screwed down upon the 60 end of the tube A².

One advantage which results from my arrangement of ports—that is, placing the ports a' in the upper flat end of the discharge-tube A and eccentric to its center, with the discharge port or opening through the cap in its center—is this: I am enabled to use a packing-washer, C, in the cap, which is held in place by the screw-threads in such manner that the hole through the washer will be coincident 70 with the discharge port or opening in the hood or tip, the relation of the holes not being disturbed by turning the washer around relative to the hood, as would be the case if the hood and washer had one or more holes arranged 75 eccentrically to their centers. Another advantage is that I am enabled to employ a spur which shall project through the port or opening b when the hood is screwed down. Another advantage is, when the hood is screwed 80 down the ports a' are closed, thus preventing liquid from escaping through those ports and thence down between the hood and discharge-tube.

I am aware that a patent granted N. D. 85 Whitin, April 29, 1842, shows a cork-tube constructed with a screw-thread upon its outer end, in combination with an internally-screw-threaded cylinder or cap having a central discharge-port, the cork-tube having a throat or 90 port in its upper end, which is closed by the screw-threaded cylinder or cap; but there are some objections to the manufacture and use of Whitin's stopper which are overcome by my construction. Thus Whitin's opening through 95 the cork-tube is expanded at the upper end, thus necessitating the employment of a core with the bulb or head at its upper end in casting it, whereas the interior of my discharge-tube is cylindrical and of substantially uniform 100 size throughout, thus permitting me to use a cylindrical core with two spurs at one end to form the ports a'.

Again, in Whitin's stopper the part B, around which liquid is discharged,

is placed below the plane of the upper end of the part E, thus necessitating a downwardly-projecting flange on the tip upon which to mount his packing-washer C, whereas, from 5 the fact that I close the upper end of my discharge-tube by means of a flat plate, a, through which the ports are made, I am enabled to attach my washer firmly to its place within the hood by means of the internal threads of the 10 flange B', the thread serving as an internal rib, which engages with the lower edge of the washer.

My construction is an exceedingly simple one, all of its parts being easily made and not 15 liable to get out of order.

What I claim is—

1. The herein-described bottle-stopper, having a discharge-tube section provided throughout its length with an opening of substantially 20 uniform diameter, and having its upper end closed by a flat plate, a, provided with ports a', in combination with a hood having a cen-

tral port, b, and a flat inner surface adapted to fit closely the flat plate a of the discharge-tube, substantially as set forth. 25

2. In the herein-described bottle-stopper, the combination, with the discharge-tube A, having at its upper end the flat plate a and ports a', of the hood provided with a central discharge-port, and the washer C, secured in place 30 by the internal thread of the hood, substantially as set forth.

3. In the herein-described bottle-stopper, the combination, with the discharge-tube having the plate a, ports a', and projecting spur a² 35 at its upper end, of the hood B B', provided with a central port adapted to receive the spur a², substantially as set forth.

In testimony whereof I affix my signature in presence of two witnesses.

STEPHEN S. NEWTON.
